UNITED STATES PATENT OFFICE

131,424

DESIGN FOR A COMBINED ERASER AND CHALK RAIL CLEANER BODY

John C. Mather, Indianapolis, Ind.

Application December 12, 1940, Serial No. 97,281

Term of patent 14 years

To all whom it may concern:

Be it known that I, John C. Mather, a citizen of the United States and a resident of Indianapolis, county of Marion, and State of Indiana, have invented a new, original, and ornamental Design for a Combined Eraser and Chalk Rail Cleaner Body, of which the following is a specification, reference being had to the accompanying drawing, forming a part thereof.

In the drawing, Fig. 1 is a perspective view of a combined eraser and chalk rail cleaner body

showing my new design, the essential features of which reside in the parts shown in full lines.

Fig. 2 is a side elevational view thereof, slightly in perspective, the broken line showings in the top of the left central portion in Fig. 1 being omitted for convenience of illustration.

I claim:

The ornamental design for a combined eraser and chalk rail cleaner body, as shown and described.

JOHN C. MATHER.
